(57) **CLAIM**

The ornamental design for a videoconferencing camera, as shown and described.

DESCRIPTION

FIG. 1 is a front perspective view of a videoconferencing camera showing our new design in a first configuration; FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is front perspective view thereof, shown in condition of use and mounted with a bracket disclosed in broken lines to illustrate an environment;

FIG. 9 is a left side elevation view thereof, shown in condition of use with a bracket and a cable disclosed in broken lines to illustrate an environment;

FIG. 10 is a front perspective view of the videoconferencing camera shown with the base pivoted in a second configuration;

FIG. 11 is a front elevation view thereof;

FIG. 12 is a rear elevation view thereof;

FIG. 13 is a top plan view thereof;

FIG. 14 is a bottom plan view thereof;

FIG. 15 is a right side elevation view thereof;

FIG. 16 is a left side elevation view thereof;

FIG. 17 is a front perspective view thereof, shown in condition of use and mounted with a bracket disclosed in broken lines to illustrate an environment; and,

FIG. 18 is a left side elevation view thereof, shown in condition of use with a bracket and a cable disclosed in broken lines to illustrate an environment.

The broken lines depict portion of the videoconferencing camera that form no part of the claimed design. The broken lines showing a bracket and cable in FIGS. 8–9, and 17–18 represent environmental structure and form no part of the claimed design. The radiating lines shown on the top-front portion of the videoconferencing camera in FIGS. 1–2, 4, 6–11, 13, and 15–18 illustrate the glowing visual effect of illumination created by light emanating from the light part of the videoconferencing camera, and form no part of the claimed design.
